UNITED STATES PATENT OFFICE.

FRANK MACOMB TILLOU, OF BAYONNE, NEW JERSEY.

AUTOMATIC POOL AND BILLIARD CUE CHALKER.

1,103,852.

Specification of Letters Patent. Patented July 14, 1914.

Application filed May 3, 1913. Serial No. 765,302.

To all whom it may concern:

Be it known that I, FRANK M. TILLOU, a citizen of the United States, residing at Bayonne, in the county of Hudson and State 5 of New Jersey, have invented new and useful Improvements in Automatic Pool and Billiard Cue Chalkers, of which the following is a specification.

The invention relates to billiard and pool 10 cue chalkers, and more particularly to the class of automatic cue chalkers.

The primary object of the invention is the provision of a device of this character wherein the chalking cube will be held so 15 as to obviate the chipping or breaking of the cube when the same is being used for the chalking of a cue for use in playing billiards or pool.

Another object of the invention is the 20 provision of a device of this character wherein the chalking cube will be actuated so as to apply the chalk to the tip of the cue without necessitating the turning of the cue or the manipulation thereof by the 25 hand as usual.

A further object of the invention is the 30 provision of a chalking device of this character which is extremely simple in construction, thoroughly reliable and efficient 80 in its purpose, strong and durable, and inexpensive in manufacture.

With these and other objects in view, the invention consists in the construction, combination and arrangement of parts as will be 35 hereinafter more fully described, illustrated in the accompanying drawing, and pointed out in the claim hereunto appended.

In the drawings:—Figure 1 is a side elevation of an automatic chalking device constructed in accordance with the invention. Fig. 2 is a vertical longitudinal sectional view thereof. Fig. 3 is an end elevation.

Similar reference characters indicate corresponding parts throughout the several 45 views in the drawing.

Referring to the drawings by numerals, the automatic chalking device comprises a cylindrical body 5 forming a handle provided with a slightly reduced closed end 6 50 in which is swiveled an eye or other suitable coupling member 7 for the connection of the handle with a suspension cord, whereby it may be hung over a billiard or pool table in convenient reach of the players of a game 55 of billiards or pool. The opposite open end of the handle 5 has an internal bore 8 of

increased size with the bore 9 at the inner closed end 6 thereof so as to provide a shoulder 10, and telescoped within the handle is a plunger 11, the same being formed 60 with a spiral slot 12 for a greater portion of its length, and in this slot is engaged a cross pin 13 which is mounted transversely in and is secured to the handle 5 so that on pressing inwardly upon the plunger 12 the latter will be caused to rotate on the inward movement thereof within the handle, the plunger being designed to support a chalking cube 14 in a manner presently described. 65

Spaced from the outer end of the plunger 12 and integrally formed therewith is an annular flange 15, while surrounding the said stem 12 between the shoulder 10 and the flange 15 is a coiled compression spring 16 which has its bearings against the said shoulder and flange and is adapted to act upon the plunger 12 for normally projecting 70 the cube 14 exteriorly of the handle. 75

Telescoped upon and suitably secured to the outer end of the plunger 12 and abutting against the flange 15 is a resilient sleeve 17 which surrounds the cube 14, and in this manner the latter is held upon the plunger so that the chalk can be readily applied to the tip of the cue when the cue is engaged 85 with the chalk 14, it being seen that by depressing the cube 14 by exerting pressure upon the cube the plunger will be forced inwardly within the handle 5 and at the same time it will be rotated, thereby automatically applying chalk to the tip of the cue by spreading a thin surface of the chalk upon the same. The resilient sleeve 17 enables the firm gripping of the chalk 14 and also the fastening of the same in alinement 90 with the outer end of the plunger 12, the sleeve being telescoped over the outer end of the plunger 12 as shown in Fig. 2 of the drawing. The outer circumference of the sleeve is of slightly less diameter than 100 the bore in the casing or cylindrical body 5 so as to avoid undue friction between the sleeve and the inner surface of the bore of the cylindrical body during the rotation of the plunger therein. The handle 5 can 105 be held within the hand of the user so that it can be forced in the desired direction when the chalk 14 is in contact with the tip of the cue to cause the rotation of the plunger 12 and thereby properly apply the 110 chalk to the tip of the said cue.

From the foregoing it is thought that the

construction and manner of operation of the invention will be clearly understood, and therefore a more extended explanation has been omitted.

5 What is claimed is:—

An automatic chalker comprising a cylindrical body having inner and outer bores therein, the outer bore being of greater size than the inner bore, a plunger slidably fitted within the inner bore and of less length than the body, an annular shoulder formed on the plunger spaced from the outer end thereof, the said plunger being formed with a spiral groove, a cross pin mounted in the body and engaged in the spiral groove so that on the inward and outward movements of the plunger the same will be rotated, a

coiled expansion spring arranged within the outer bore of the body and surrounding the plunger and having its outer end working 20 against the shoulder, a chalk cube arranged in alinement with the outer end of the plunger, and a resilient sleeve telescoped over the outer end of the plunger and also over the cube for connecting the same to the 25 plunger, the said sleeve being of a length to extend over a major portion of the cube.

In testimony whereof I affix my signature in presence of two witnesses.

FRANK MACOMB TILLOU.
